US0D1076797S

(12) **United States Design Patent** (10) Patent No.: **US D1,076,797 S**
(45) Date of Patent: ** May 27, 2025

(54) **CHARGER**

(71) Applicant: **Anker Innovations Technology Co., Ltd.**, Changsha (CN)

(72) Inventors: **Jie Cao**, Shenzhen (CN); **Hongzhi Yan**, Shenzhen (CN); **Zhichao Xiong**, Shenzhen (CN)

(73) Assignee: **Anker Innovations Technology Co., Ltd.**, Changsha (CN)

(**) Term: **15 Years**

(21) Appl. No.: **29/981,806**

(22) Filed: **Jan. 2, 2025**

(30) **Foreign Application Priority Data**

Jul. 1, 2024 (CN) 202430408081.3

(51) **LOC (15) Cl.** **13-02**

(52) **U.S. Cl.**

USPC **D13/103**

(58) **Field of Classification Search**

USPC D13/103, 107, 104, 108, 110, 112, 118, D13/119, 184, 137.1; D14/251, 253

CPC H02J 7/0047; H02J 7/00; H02J 7/0042; H01M 50/10

CLAIM

The ornamental design for a charger as shown and described.

DESCRIPTION

FIG. 1 is a front top perspective view of a charger showing our new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the charger that form no part of the claimed design.

1 Claim, 8 Drawing Sheets
